COLLAPSIBLE TUBE CAP

Tulio A. Brige, Caracas, Venezuela

Application July 17, 1936, Serial No. 91,200

1 Claim. (Cl. 221—60)

The invention relates to a tube cap and more especially to caps for collapsible tubes for holding paste, powder or other materials, for example, dental toothpaste or powder.

5 The primary object of the invention is the provision of a cap of this character, wherein the same is fitted with the pouring spout or mouth of a collapsible tube so that when in open position it will remain connected and in this fashion avoiding the loss or misplacement of such cap which is usually the case when the cap is completely separable from the tube and also that is capable of being secured in closing position on the spout or mouth of the tube to avoid loss of 10 the contents thereof.

Another object of the invention is the provision of a cap of this character, wherein the construction thereof is novel in that said cap can be rotated on the mouth or spout of a collapsible tube for the fastening or unfastening thereof and when unfastened can be moved to a position to 20 permit convenient dispensing of the contents of the tube without complete separation of the cap therefrom.

25 A further object of the invention is the provision of a cap of this character, wherein the same is socketed to fit the conical shaped dispensing spout or mouth of a collapsible tube, the said cap being readily and easily manipulated for the opening and closing of such tube.

30 A still further object of the invention is the provision of a cap of this character, which is simple in construction, thoroughly reliable and effective in operation, convenient for handling, affording a closure for a collapsible tube, readily and easily opened, and inexpensive to manufacture and install.

With these and other objects in view, the invention consists in the features of construction, 40 combination and arrangement of parts as will be hereinafter more fully described, illustrated in the accompanying drawing, which discloses the preferred embodiment of the invention and pointed out in the claim hereunto appended.

45 In the accompanying drawing:

Figure 1 is a fragmentary elevation of a collapsible tube showing a cap constructed in accordance with the invention applied and in open position.

50 Figure 2 is a sectional view on the line 2—2 of Figure 1 looking in the direction of the arrows.

Figure 3 is a sectional view on the line 3—3 of Figure 2 looking in the direction of the arrows and showing the cap in closed position.

Figure 4 is a sectional view on the line 4—4 of Figure 3 looking in the direction of the arrows.

Figure 5 is a perspective view of the connecting link between the cap and the tube.

Figure 6 is a sectional view on the line 6—6 of Figure 1 looking in the direction of the arrows.

Similar reference characters indicate corresponding parts throughout the several views in the drawing.

Referring to the drawing in detail, A designates generally a portion of a collapsible tube for containing paste, powder or other material, as for example, toothpaste or tooth powder, and at one end of this tube is an outwardly tapered or conical shaped mouth piece or dispensing spout, nipple or the like 10, it having a delivery passage 11 leading from the interior of the tube and laterally to one side of said mouth, spout, nipple or the like 10 so that the contents of the tube can be readily discharged or dispensed through this passage 11 for consumption.

Adapted to be fitted onto the mouth, spout, nipple or the like 10 is a closure cap 12 having a conical shaped socket 13 closed at one end and open at the other end and corresponding to the mouth, spout, nipple or the like 10 for receiving or accommodating the same. This closed end of the cap 12 has formed therein a circular shaped recess 14 for accommodating the springy head 15 of a double prong link 16 formed from a single length of wire, the prongs of this link 16 being slidably fitted in a guide way 17 provided in the mouth, spout, nipple or the like 10, it being apparent from Figures 2, 3 and 4 of the drawing that the said cap 12 when interfitted 20 with the link 16 at its head 15, the said cap 12 can be freely rotated and that the said head 15 is frictionally latched in the recess 14.

One of the prongs of the link 16 is formed with a lateral stop extension 18 engageable with a stop shoulder 19 interiorly of the guide way 17 at the outer end thereof and in this manner the link 16 is limited in its sliding movement in an outward direction within the mouth, spout, nipple or the like 10. The other prong of the link 16 is formed with an angularly disposed terminal extension 20 which is rigid against the prong having the stop extension 18 so that these prongs engaged in the guide way 17 will be held separated to effect the effective cooperation of the extension 18 with the shoulder 19 and in this fashion permanently connecting the cap 12 with the tube for permitting the shifting of the cap outwardly and inwardly with respect to the mouth, spout, nipple or the like 10. The cap 12 when shifted 30 35 40 45 50 55

inwardly will be telescopically fitted onto the mouth, spout, nipple or the like 10 so as to close the passage 11 to prevent dispensing of the contents of the tube. On the outward shifting of the cap 12 the passage 11 is opened and the contents of the tube can be readily dispensed by the collapsing of such tube. Formed exteriorly on the mouth, spout, nipple or the like 10 is a screw thread 21 while interiorly of the cap 12 at its open end is a companion screw thread 22 for the thread 21 so that by rotating the cap when moved inwardly these threads 21 and 22 will cooperate for the fastening of the cap in closed position.

15. The material dispensed through the passage 11 will be sheared when the cap is rotated for the fastening of the same in closed position on the mouth, spout, nipple or the like 10 and thereby avoiding undue waste of material.

The cap 12 is at all times maintained connected with the tube so as to eliminate loss of such cap which frequently occurs with the completely separable cap of a collapsible tube.

What is claimed is:

1. In a container, a mouth piece thereon and having a discharge laterally thereof, a screw closure cap separable engaged with said mouth piece and having a circular recess interiorly thereof, said mouth piece having a longitudinal guide way therein, a double prong link having a springy head frictionally engaged in the cylindrical recess in the cap for rotation of the latter upon said head, the double prongs of the link being slidably fitted in the guide way, and a lateral extension on one of the prongs and active on the other prong for the slidable latching of the link in said guide way.

TULIO A. BRIGE.
